Apparatus for, and Method of, Chromatic Printing.

No. 237,612.

Patented Feb. 8 1881.

UNITED STATES PATENT OFFICE.

GUSTAV SCHWARZWALD, OF NEW YORK, N. Y., ASSIGNOR TO THE POLY-CHROMATIC PRINTING COMPANY, OF SAME PLACE.

APPARATUS FOR AND METHOD OF CHROMATIC PRINTING.

SPECIFICATION forming part of Letters Patent No. 237,612, dated February 8, 1881.

Application filed June 21, 1880. (No model.)

To all whom it may concern:

Be it known that I, GUSTAV SCHWARZWALD, of the city, county, and State of New York, have invented certain new and useful Improvements 5 in Apparatus for and Method of Producing Polychromatic Prints, of which the following is a specification.

This invention has reference to an improved machine and method of producing designs in 10 any desired colors on a dark or light ground of paper, wood, metal, or other fabric, whether in straight lines or in variously-formed patterns, for the purpose of obtaining polychromatic effects, which were heretofore not obtainable in the printing or lithographic arts.

The invention consists in applying to any object which has been partly or entirely covered with a layer of adhesive material pulverized colors by means of a vertically-movable distributor. The distributor is constructed of perforated shelves, which support a series of color-tubes that are arranged according to any suitable design and closed at their lower ends by bolting-cloth. The finely-pulverized 25 colors are deposited by the sudden concussion of the distributor with a pattern-frame placed upon the object, and distributed evenly either mechanically by properly-constructed brushes or sweeps or pneumatically by air-pressure. 30 By a repetition of this process a variety of colors and any desired blending of the same may be obtained.

In the accompanying drawings, Figure 1 represents a vertical longitudinal section of 35 my improved machine for producing polychromatic prints. Fig. 2 is a sectional side elevation of the same with two color-distributors of different construction. Fig. 3 is a vertical central section of one of the color-tubes on 40 an enlarged scale. Fig. 4 shows two cross-sections of differently-shaped tubes. Fig. 5 represents a sectional top view of the machine, showing the color-distributer and the reciprocating carriage for the pattern-frame. Fig. 6 45 is a top view of a pattern-frame with curved portions. Fig. 7 is a detail vertical section of the distributor and color-tube, shown in position on the pattern-frame for depositing the color. Figs. 8 and 9 are respectively a top

view and a vertical longitudinal section of the 50 mechanism for operating the color-distributing brushes or sweeps; and Fig. 10 is a top view of a portion of a label or other print produced by my improved method.

Similar letters of reference indicate corresponding parts.

Referring to the drawings, A is the supporting-frame of my improved machine for producing polychromatic prints. The frame A is provided with longitudinal top rails, a, on which 60 is guided a reciprocating carriage, B, the carriage being operated either by hand or power, as desired.

Upon the carriage B the platen of the machine is arranged, and the paper or other object to be produced in colors placed upon the platen, the paper having first been covered, either partly or entirely, with a layer or covering of any suitable fatty ink or an adhesive substance. This layer forms the ground upon 70 which all the colors are laid on in succession.

Upon the carriage B and the paper or other object to be printed is placed a pattern-frame, C, composed either of parallel bars which taper toward their upper narrow edge or of 75 angular oblong curved strips, as shown in Fig. 6. A pattern-frame, C, with straight strips is employed whenever the colors are to be laid on in right lines, a pattern-frame with angular or curved strips whenever a special design is 80 to be produced. The pattern-frame C is secured by clamp-screws or otherwise to an open frame, D, which is hinged at one side to the carriage B, and provided at the opposite side with a handle for readily raising or lowering 85 the pattern-frame in removing and inserting the paper to be printed upon.

The frame A is extended above the carriage B, and supports either a bracket-shaped arm, A', or a braced top part, A'', which serves to 90 guide and support the vertically-movable rod E of the color-distributer F, which is applied to the lower end of the rod E by suitable adjustable fastening devices. This color-distributer F forms an essential element of my 95 invention, and is worked either by a hand-lever and weight, or by a lever-and-treadle connection, or by power and suitable working

mechanism, so as to be quickly lowered upon the pattern-frame of the carriage or raised therefrom.

The color-distributer is constructed of two 5 perforated shelves, *b b*, in the holes of which a series of color-tubes, *F'*, is supported. The lower part of the color-tubes *F'* is made of conical shape, and the upper provided with a rim or funnel-shaped portion, by which the 10 tubes are held steadily in the holes of the shelves *b b*. The color-tubes *F'* are preferably made of glass, of round or flat cross-section, closed at their lower ends by bolting-cloth, wire-gauze, or other fabric, as shown in Figs. 15 3 and 4, and filled with finely-ground color. These color-tubes *F'* are disposed of in the shelves of the distributer *F*, according to the design to be produced, they being placed closer to each other or farther apart, according to the 20 size of the surface to be colored, so that any desired tint can be produced. By lowering the color-distributer *F* on the pattern-frame a small quantity of color is dropped onto the paper on the platen by the concussion of the 25 distributer with the pattern-frame. After the color is thus deposited within the strips of the pattern-frame the distributer is raised by the lifting mechanism away from the frame.

As the quantity of color discharged by each 30 color-tube is very small and deposited in such a manner as to cover only a small part of the surface of the paper, the next step is to produce the uniform distribution of the colors over the entire surface of the same. This is accomplished either 35 mechanically by means of brushes or sweeps, which are operated by hand or by suitable mechanism, or pneumatically by air-pressure. For the latter purpose the color-distributer is closed at the top, so as to form an air-chamber, 40 which is connected by its hollow guide-rod and a suitable hose with a fan or other air-compressing device. The air is allowed to enter the distributer or is shut off by a valve of the guide-rod, so as to put on or interrupt 45 the air-pressure. The lower part of the color-distributer bears, by a felt or other elastic facing, tightly upon the pattern-frame *C*, the outer frame, *D*, of which is also lined with felt, so as to bear tightly upon the strips of the 50 pattern-frame. The air is evenly distributed in the air-chamber above the color-tubes by a horizontal diaphragm, (shown in Fig. 2,) and conducted through the holes of the shelves not taken up by color-tubes into the spaces 55 enclosed between the strips of the pattern-frame, the bottom of the color-distributer, and the paper on the platen. The air acts upon the colors deposited from the tubes by the concussion, distributing them uniformly over 60 the entire surface of the paper between the straight or curved strips of the pattern-frame. This arrangement of distributing the colors is shown clearly in Fig. 2, while the method of distributing the colors by brushes or sweeps 65 is shown in Figs. 1 and 5. The brushes *G* employed for this purpose are covered with bea-

ver-fur, and again covered at those portions which are not required for spreading the colors with bands of paper, leather, or other suitable fabric. The brush is drawn by hand 70 once or twice over the pattern-frame, and locked after use to retaining hooks or clasps of the hinged frame *D*, so as not to get detached therefrom when the frame is thrown up for placing another sheet in position. The 75 soft fur of the beaver-skin not only takes up the surplus color, so as to use it for the next sheet, but it produces also a perfectly even distribution of the colors over the surface of the paper. If desired, the distribution of the 80 colors may also be produced by fur-covered revolving brushes which are set into a perforated frame, which perforations correspond with those of the shelves of the distributer, the brushes being rotated by reciprocating 85 rack-bars which mesh with small pinions at the upper ends of the brush-spindles, as shown in detail in Figs. 8 and 9. For most purposes, however, the fur-brushes operated by hand are sufficient, though for larger manufacturing 90 purposes the brushes may be so constructed that they can be worked by power. After the colors are laid on the carriage is drawn side- 95 wise, the hinged pattern-frame thrown up, and the paper removed. A new sheet is then 95 placed in position and properly registered thereon, the pattern-frame brought down on the paper and carried with the carriage into position below the distributer. The color is then deposited by lowering the distributer, 100 and finally evenly distributed over the surface to be colored by the brushes, as described. In this manner a variety of tints, in right or intersecting lines and in any desired pattern, 105 and in plain or blended colors, may be produced, and thus an infinite variety of polychromatic designs for fancy labels, checks, and other purposes obtained.

The advantage of the apparatus consists, mainly, in the fact that any number of different colors can be laid on with a perfect register by one operation, and thereby a more variegated effect be obtained.

Having thus described my invention, I claim as new and desire to secure by Letters Patent—

1. In an apparatus for producing polychromatic prints, the combination, with a reciprocating platen-carriage having an interchangeable pattern-frame, of a vertically-movable 120 color-distributer, and of means, substantially as described, whereby the colors are evenly distributed on the sheets after the colors have been deposited, substantially as and for the purpose set forth.

2. In an apparatus for producing polychromatic prints, a color-distributer consisting of perforated shelves, and of a series of color-tubes supported thereon, substantially as set forth.

3. The method herein described of producing polychromatic prints, consisting in laying

an adhesive covering over the surface to be covered, then depositing small quantities of finely-pulverized colors on the so-covered surface, and, lastly, distributing the colors evenly over the adhesive surface, substantially as and for the purpose set forth.

4. In an apparatus for producing polychromatic prints, the combination, with a reciprocating carriage, of a pattern-frame, a vertically-guided color-distributer, and mechanism,

substantially as described, for raising and lowering the same, substantially as set forth.

In testimony that I claim the foregoing as my invention I have signed my name, in the presence of two witnesses, this 17th day of 15 June, 1880.

GUSTAV SCHWARZWALD.
